[57] CLAIM

The ornamental design for an archery compound bow cam, as shown and described.

DESCRIPTION

FIG. 1 is a side elevation of a cam for a compound bow, showing our new design;

FIG. 2 is an enlarged left side elevational view thereof;

FIG. 3 is an enlarged right side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken line showing of environment in FIGS. 1-7 is for illustrative purposes and forms no part of claimed design.
